UNITED STATES PATENT OFFICE.

HENRY W. MERRITT, OF SYRACUSE, NEW YORK, ASSIGNOR TO THE MONARCH TYPEWRITER COMPANY, OF SYRACUSE, NEW YORK, A CORPORATION OF NEW YORK.

TYPE-WRITING MACHINE.

No. 901,982.

Specification of Letters Patent.

Patented Oct. 27, 1908.

Application filed February 10, 1905. Serial No. 245,078.

To all whom it may concern:

Be it known that I, HENRY W. MERRITT, citizen of the United States, and resident of Syracuse, in the county of Onondaga and 5 State of New York, have invented certain new and useful Improvements in Type-Writing Machines, of which the following is a specification.

My invention relates more particularly to 10 the ribbon mechanism of that class of type-writing machines commonly called "visible writers", and wherein the writing is visible to the operator as he writes. In such machines it is usual to employ in connection 15 with the ribbon a ribbon vibrator or carrier, which term, as used herein, means any device for moving the ribbon to and from the printing point under the control of the printing keys.

20 One object of my invention is to provide a construction wherein a ribbon having a plurality of fields of different characteristics may at each printing operation be moved to cover the printing point with any of its 25 fields, as desired.

Another object is to provide means for dispensing at will with the crosswise feed of the ribbon in that class of machines employing a ribbon vibrator and wherein the ribbon has 30 both a crosswise and a lengthwise feed.

Another object is to provide means to enable a ribbon of more than one color, commonly called a polychrome ribbon, to be employed in the last named class of machines.

35 Another object is to dispense at will in a machine of the last named class with the vibratory movement of the ribbon so that the latter may be maintained quiescent and without the printing field during the printing operation.

To the above and other ends which will subsequently appear the invention resides in the features of construction, arrangements of parts, and combinations of devices to be 45 herein after more fully described and particularly pointed out in the concluding claims.

In the accompanying drawings, Figure 1 is a vertical front to rear sectional view, 50 taken about centrally, of one form of type-writing machine embodying my invention; Fig. 2 is a front elevation of the machine partly in section and with certain parts omitted; Fig. 3 is a detail view of part of the 55 crosswise ribbon feed mechanism; Fig. 4

is an enlarged fragmentary top plan view showing parts of the ribbon mechanism; Figs. 5, 6 and 7 are enlarged top plan views similar to Fig. 4, but omitting parts shown in said Fig. 4 and showing other parts in positions different from those in which they appear in said Fig. 4; Fig. 8 is a perspective view of one of the elements, hereinafter called a switching member or slide, of the ribbon mechanism. Figs. 9, 10, 11 and 12 60 are detail front elevations, partly in section, showing the positioning and stop devices in different positions; Fig. 13 is an enlarged side elevation of Fig. 9; Fig. 14 is an enlarged sectional view taken on the line $x-x$ 70 of Fig. 11; Figs. 15 and 16 are detail views of parts of the stop device.

I have illustrated my invention as embodied in the Monarch typewriting machine, but I desire it to be understood that it may 75 be adapted to other forms of writing machines.

In the drawings, 1 indicates the base of a typewriting machine supporting corner posts 2, which latter sustain a top plate 3. 80 Key levers 4, each provided with a restoring spring 5, are fulcrumed on a fulcrum plate 6. A sub-lever 7 is pivoted at 8 to each key lever and the lower portion of said sub-lever is adapted to coöperate with a fixed 85 abutment 9. The upper end of each sub-lever is connected by a link 10 with a type bar 11 which is one of a segmentally arranged series, each type bar whereof is seated in a radial slot 12 formed in a segmental 90 type bar support 13. The heel of each type bar is perforated to permit of the passage of a segmental pivot wire 14 contained in a groove in the top of the segmental type bar support. The type bars instead of being 95 pivoted on a fulcrum wire, as herein shown, may each be provided with individual hangers and pivots. A type rest 15 normally supports the type bars at their free ends and said bars when suitably actuated coöperate 100 with a platen 16 mounted in a carriage 17, said carriage being guided and supported by anti-friction balls 18 which are seated in grooved rails 19 on the carriage and in oppositely grooved rails 20 secured to brackets 105 21 fixed to the top plate of the machine. The carriage 17 is provided with a feed rack 22 which normally meshes with a pinion 23, the latter being operatively connected with an escapement wheel 24. Feed dogs 25 are 110

adapted to coöperate with the escapement wheel, said feed dogs being mounted on the upright arm of a pivoted dog rocker 26, the horizontal arm 27 whereof is connected by 5 a wire or rod 28 with the central, rearwardly extending arm 29 of a universal bar frame 30 pivoted in the base of the machine at 31. The frame 30 carries a universal bar 32 which extends from side to side of the machine beneath the series of key levers 4 and the spacing levers (not shown) and is adapted to be actuated by said levers when the latter are depressed during printing or spacing operations. The carriage 17 is connected 10 by a strap or band 33 with a spring drum 34, which constantly tends to draw the carriage to the left, the result being that when the universal bar 32 is actuated, the escapement mechanism above described is caused 15 to be operated in a known manner and thereby to permit of letter space movements of the carriage.

A pair of ribbon spools 35, arranged above the top plate and forwardly of the platen, 20 one at each side of the machine, receive a ribbon 36 which, as herein shown, is divided longitudinally into fields *a* and *b* of different characteristics; for example, the field *a* may be of one color as black, and the field *b* may be of another and different color, as red, or the field *a* may be copying ribbon and the field *b* record ribbon. The ribbon 36 may be fed lengthwise from either spool to the other by any suitable means. The drawings illustrate a ribbon feed mechanism which is similar to that employed in the Monarch typewriting machine, and which is explained in the United States patent to Jacob Felbel and Carl Gabrielson, No. 35 703,339, dated June 24th, 1902. Each ribbon spool 35 is carried by an upright shaft 37 which rotates in a fixed bearing 38 and has secured to its lower end a small beveled gear 39. The gear 39 meshes with a beveled 40 pinion 40 secured to the forward end of a horizontal shaft 41 which shaft has its bearings in lugs 42 and 43 depending from the under side of the top plate. The shaft 41 carries at its rear end a beveled pinion 44 45 which is adapted to mesh with a beveled pinion 45 mounted on a driving or power shaft 46, said shaft being supported in bearing lugs 47. Rotary movement from the spring drum 34 is transmitted to the driving 50 shaft 46 by beveled pinions 48 and 49, the pinion 48 being operatively connected with the spring drum and the pinion 49 with the driving shaft. It will be understood that both ribbon spools are provided with similar 55 gear trains which are adapted to be actuated from driving pinions 45 on the driving shaft 46. As explained in the above cited patent, the driving or power shaft 46 is capable of longitudinal movement and the longitudinal 60 position of said shaft determines which driv-

ing pinion 45 will be in mesh with its co-operating pinion 44 and which ribbon spool will be turned to wind the ribbon thereon.

Midway between the ribbon spools 35 the ribbon 36 is threaded through a ribbon vibrator or carrier 50 which is supported and guided in the upright arms 51 of a supporting bracket 52 secured by screws 53 to the top plate of the machine. The lower portion of the vibrator or carrier 50 is bifurcated and carries a cross-pin 54 which is embraced by the slotted forward end of an operating lever 55 fulcrumed at 56 in a lug 57 depending from the top plate. The rear arm of the operating lever 55 has formed in it an elongated slot 58 which receives a pin or stud 59 secured at the top of a vertically arranged link 60. The link 60 is made for convenience in several parts which screw into one another or are otherwise suitably secured together, and the upper part 61 of said link is flattened and, besides carrying the stud 59, is provided with a downwardly and forwardly bent arm 62 (Fig. 3). At its lower end the link 60 is pivoted at 63 to the arm 29 of the universal bar frame. The link 60 is adapted to be swung about the pivot 63 in order to cause the stud 59 to move longitudinally of the slot 58 so that said link may engage the operating lever 55 at varying distances from its fulcrum 56 and thereby vary the throw of the ribbon carrier or vibrator 50. The means employed to swing the link 60 about its pivot 63 and longitudinally of the lever 55 comprises an eccentric controller or member designated as a whole by the numeral 64, which member is slidably mounted upon the driving shaft 46 and is adapted to coöperate with the strap formed near the top of the link 60 by the part 61 and its bent arm 62. The eccentric member 64 comprises an eccentric working face 65, a tapered or cam portion 66 and a sleeve portion 67, which latter is formed with a circumferential groove or depression 68. A screw 69 passes into the sleeve portion 67 of the eccentric member 64 and enters an elongated slot or groove 70 in the driving shaft 46. The eccentric member 64 is thereby slidably connected with the driving or power shaft 46 and is caused to rotate by and with said shaft but may be moved longitudinally of said shaft without affecting the latter. The shaft 46 may also be moved endwise without affecting the member 64. Pivoted forwardly of the link 60 to the arm 29 of the universal bar frame at 71 is a two-part link 72, the upper portion of which is bent or off-set at 73 and 74 so that the flattened top part 75 of said link stands to the left and forwardly of the top of the link 60; and so that a stud 76 secured to said flattened portion 75 is adapted to engage with the slot 58 of the operating lever at the left side of the latter and forwardly of the

stud 59 which engages with the slot 58 at the right side of the operating lever. For most work the stud 76 stands normally out of engagement with the slotted operating lever 55. The links 60 and 72 are capable of a slight movement transversely of the operating lever 55 so as to provide for the alternate engagement of the studs 59 and 76 of said links with the slot 58 in the operating lever. A horizontally disposed spiral spring 77, having one end secured to the connecting rod 28 and the other end to the link 60, tends to constantly swing the latter rearwardly about its pivot 63.

15 The movement of the link 60 transversely of the operating lever 55 and the similar transverse movement of the other link 72 are controlled by a switching member or slide designated as a whole by the numeral 20 78 and best seen in Fig. 8 of the drawings. The switching member 78 comprises first a longitudinal body portion 79, second an arm 80 projecting forwardly from the top of the left-hand end of the body portion 79 25 and provided near its end with a slot 81, third, a wire loop 82 projecting forwardly and horizontally from the central part of the body portion 79, and fourth an arm 83 projecting forwardly from the right-hand 30 end of the body portion and provided with a perforated collar portion 84 which may be secured to the arm 83 in any suitable manner, as by soldering. The slot 81 is so shaped as to permit of the insertion of the 35 cylindrical lower portion of the upper part of the link 72 in assembling the parts, and further to permit of the vertical play within said slot of the flattened upper end 75 of said link 72 when the latter is reciprocated under the influence of the universal bar during the operation of the machine. In assembling the mechanism the upper flattened part 61 of the link 60 may be inserted 40 between the sides of the wire loop 82, which latter may thereafter be riveted in the body portion 79 of the switch 78 in a manner best indicated in Fig. 4. When so assembled, the part 61 may move longitudinally of the 45 loop 82 under the influence of the eccentric face 65 and said part 61 may also move up and down transversely of the loop when the link 60 is reciprocated by the universal bar.

The longitudinal movement of the eccentric member 64 is controlled by a second switching member 85 (Fig. 2), which comprises a vertically disposed arm 86 terminating at the top in a perforated collar portion 87 and at the lower end in a fork 88 which fits into and embraces the groove or depression 68 in said eccentric member. The collar portion 87 of the switch member 85 fits on the inner end of a pull and push rod 89 and said collar portion is secured thereto by a headed screw 90. The rod 89 extends horizontally beneath the top plate and termi-

nates near the right-hand side of the machine in a collar 91 provided with a forwardly extending pin 92. The rod 89 is surrounded for the greater part of its length by a sleeve 93 which is provided near its left-hand end with a spline 94. The sleeve 93 has its bearings in the right-hand bearing lug 47 of the driving shaft 46 and in a right-angled bracket 95 which is secured to the under side of the top plate by headed screws 96. The bracket 95 is slotted to permit of endwise play of the spline 94 therethrough, but the said spline fits the slot in the bracket 95 with sufficient snugness to prevent the sleeve 93 from turning in its bearings, although it moves freely longitudinally therein. The rod 89 moves freely longitudinally of the sleeve 93 which latter serves as a bearing for the said rod. As best shown in Fig. 4, the collar portion 84 of the switching member 85 fits over the inner or the left-hand end of the sleeve 93 and is secured to said sleeve by a set screw 97. The switching member 78 is maintained constantly in a horizontal position, by the spline 94 of the sleeve 93 with which latter the member 78 is secured in a fixed relation by a set screw 97. As seen in Fig. 4, the collar portion 84 of the switching member 78 is positioned between the bracket 95 and the collar portion 95 87 of the switching member 85.

A collar 98 is fixedly secured to the sleeve 93, between the bracket 95 and the bearing 47 of said sleeve, by a set screw 99. A coiled spring 100 surrounds the sleeve 93 between the sleeve bearing 47 and the collar 98, which latter is normally pressed by said spring against the right-hand face of the bracket 95 thereby positioning the sleeve 93 and the switching member 78 mounted on 105 said sleeve, as indicated in Fig. 4.

As best seen in Figs. 9 and 4, the pin 92 at the right-hand end of the rod 89 is embraced by the fork of a bifurcated crank arm 101, the collar portion 102 whereof is fixedly secured to the rear end of a horizontally disposed and forwardly extending rock shaft 103. The horizontal portion of the rock shaft 103 extends through and terminates slightly in front of the front plate 104 of 110 the machine.

The forward portion of the rock shaft 103 is flattened and is turned up at right angles to the body of the shaft forming a crank arm 105, the end whereof is provided with 115 a handle or finger piece 106. The rock shaft 103 has its bearings in bearing plates 107 and 108 which are respectively secured to the right hand lugs 42 and 43 by headed screws 109. A collar 110 is fixedly secured to 120 the rock shaft 103 and abuts against the forward face of the rear bearing plate 108.

Another collar 111 is fixedly secured in any suitable manner to the rock shaft and abuts against the rear face of the forward 130

bearing plate 107. The collars 110 and 111 serve to prevent endwise motion of the rock shaft 103.

- Integral with the collar 111 is a positioning member 112 which, as herein shown, is in the form of a sectoral plate extending to the left and downwardly from the rock shaft and having its periphery formed with depressions or notches 113, 114, 115 and 116. 5
- 10 A check or locking spring 117 is fixedly secured to the under side of the top plate in any suitable manner and is adapted to engage the depressions or notches in the positioning member 112.
- 15 The inner side of the crank arm 105 is adapted to coöperate with different faces or stop portions of a stop member 118 which comprises a perforated hub 119; side faces or stops 120; cut-aways or depressions 121 20 between the hub 119 and the side stops 120; and end faces or stops 122 and 123. The stop member 118 is fixedly connected, as by a driving fit or in any other suitable manner, with a knurled thumb wheel 124 which 25 is longitudinally perforated to receive a shouldered screw 125 which screws through the front plate 104 and through a reinforcing washer 126 and a nut 127 placed in front of and behind said front plate. Between 30 the front washer 126 and the shoulder of the shouldered screw 125 is a limiting stop 128 which comprises a perforated hub portion 129 from the right-hand side of which a lug 130 projects forwardly of the machine, said 35 limiting stop being shown in detail in Fig. 16. The limiting stop 128 and the washer 126 and nut 127 are fixedly held by the threaded portion of the screw 125, while the thumb wheel 124 and the stop member 118 rotate 40 on the shouldered portion of said screw, being frictionally controlled by an annular cup-like spring plate 131 which is interposed between the rear face of the thumb wheel 124 and the front face of the limiting stop 128, and is shown in detail in Fig. 15.
- 45 If the knurled thumb wheel 124 be turned so as to rotate the stop member 118 to the position indicated in Figs. 2 and 9 and if, by means of the handle 106, the rock shaft 50 103 be rotated leftward until the crank arm 105 contacts with the side stops 120, as indicated in said figures, the positioning member 112 will be rotated until its depression 113 is engaged by the locking spring or 55 check 117 and the switching members 78 and 85 and the parts associated with and controlled by them will be in the positions indicated in Figs. 2 and 4. With the parts so positioned, the ribbon will be fed longitudinally and will also be given a variable crosswise feed so that the type impressions will make a serpentine or wavy path lengthwise of the ribbon and extending from side to side thereof. If a ribbon of uniform

character be in place on the machine, a ribbon having a plurality of fields of different characteristics may be substituted therefor in a known manner. A ribbon of the last named kind is represented in the drawings and indicated therein by the numeral 36. 65 The ribbon 36 is shown as made up of two longitudinal stripes or fields *a* and *b* and if these be colored, as hitherto suggested, respectively black and red, and the mechanism be allowed to remain in the relations indicated in Figs. 2 and 4, some of the type impressions will be printed in black, others in red, and others partly in black and partly in red, giving a variegated or parti-colored effect which is sometimes desirable in ornamental typewriting. Usually, however, it is desired to print all the letters of a word or a succession of words in one color. 75 80

Suppose first that it be desired to print in black alone. The handle 106 is first swung to the right, then by means of the thumb wheel 124 the stop member 118 is rotated to the right to the position indicated in Fig. 10, with the depressed part 121 in contact with the limiting lug 130, and finally the handle 106 is swung to the left until the crank arm 105 contacts with the end stop 122 when, as indicated in Fig. 10, the depression 114 of the positioning member 112 will be engaged by the locking spring 117. Comparing Fig. 10 with Fig. 9 it will be noted that the rock shaft 103 has been rotated rightward through an arc which is represented on the periphery of the sectoral positioning member 112 by the distance between the depressions 113 and 114. This rotary movement of the rock shaft causes its rear crank arm 101, acting on the pin 92, to move the slide rod 89 endwise and through the sleeve 93 and thereby to draw the eccentric member 64 to the right to the position indicated in Fig. 5 with the switch member 85 in contact with the switching member 78. It will be apparent from an inspection of said figure that the eccentric face 65 has been withdrawn completely 110 from its strap formed by the upper part 61 of the link 60 and the forward bent arm 62 of said link. The separation of the eccentric from its strap permits the draw spring 77 to swing the link 60 rearwardly about its pivot 115 63 until the part 61 contacts with the body portion 79 of the switch member 78, at which moment the stud 59 engages the operating lever 55 at the greatest possible distance from the fulcrum 56 of said lever. If the printing devices be operated with the parts in the relations indicated in Fig. 5, the link 60 acting on the operating lever 55 at the furthest point possible from the fulcrum 56 of the lever will swing the latter upward to the least height through which it can be thrown by said link 60 during the operation 120 of the machine. With the parts related as 125

last described, this upward movement of the lever 55 is constant and unvarying and the mechanism is so proportioned that the ribbon vibrator is always thrown thereby so as 5 to present the same part of the width of the ribbon to the action of the printing types. The path of the type impressions will be in a straight line longitudinal of the upper or black field *a* of the ribbon.

10 Sometimes it is desirable, as in preparing stencils for mimeograph work, to cause the types to strike directly against the stencil or other paper without the interpositioning of the ribbon between them. I have provided 15 means to accomplish this result by mechanism which prevents either of the links 60 or 72 from actuating the operating lever 55, so that the latter will remain quiescent in normal position during the operation of the 20 printing keys. To accomplish this result the handle 106 is swung to the right and the stop member 118 rotated leftward to the position indicated in Fig. 11 with the depression 121 in engagement with the limiting lug 25 130, after which the handle 106 is swung leftward until the crank arm 105 contacts with the end stop 123, which latter is at a distance from its center of rotation slightly greater than is the distance of the end stop 122 from 30 said center. Consequently the rock shaft 103 is rotated a short distance to the right of the position indicated in Fig. 10 and the locking spring 117 disengaging from the 35 notch 114 engages with the notch 115 in the positioning member 112. During this rotary movement of the rock shaft 103, its rear crank arm 101 pulls the slide rod 89 still further to the right and the switch member 85, which it will be recalled is 40 now in contact with the switch member 78, will act on the latter to pull it to the right against the pressure of the coiled spring 100, the sleeve 93 moving longitudinally with the rod 89 and sliding through the bearings 45 47 and 95. During this rightward movement of the switch member 78 the upper portion of the link 60 which is controlled by the wire loop 82 will be swung transversely of the operating lever 55 until the stud 59 is disengaged from said lever, while at the same time the link 72 is swung to the right until its stud 76 stands but a short distance from the operating lever but out of engagement therewith, there being sufficient spring or give in 55 the two links to permit of this movement transversely of the operating lever. The parts will now be in the positions indicated in Fig. 6, neither link being engaged with the operating lever, so that when the printing 60 devices are actuated the ribbon vibrator will remain quiescent in normal position and the ribbon will not be interposed between the types and the paper.

If it be desired to print only on the red 65 stripe *b* of the ribbon, the handle 106 is

swung rightward until the last notch or depression 116 of the positioning member engages with the locking spring 117, the notch 116 and the locking spring 117 being so proportioned and related that the check forms 70 a positive stop for the positioning member 112 and there is no danger of overthrow. This further rotation of the rock shaft 103 causes the crank arm 101, acting on the slide rod 89, to draw the two switch members 85 75 and 78 still further to the right to the position indicated in Fig. 7, thereby increasing the compression of the spring 100 and bringing the stud 76 into engagement with the slot 58, and thus operatively connecting the 80 link 72 with the operating lever 55. The link 72 is guided and controlled by the slot 81 in the arm 80 so that said link always acts on the operating lever 55 at a fixed distance from the fulcrum of the latter. The 85 point at which the link 72 acts on the operating lever is nearer the fulcrum of the latter than is the point at which the link 60 acts on said lever when the parts are positioned as indicated in Fig. 5. The result is 90 that the lever 55 has a constant swing under the influence of the link 72 which is greater than is the constant swing of the lever under the influence of the link 60, and under the influence of said link 72 the ribbon vibrator 95 is swung to a greater height, the parts being proportioned so that the lower field or red stripe *b* of the ribbon will be presented at the printing point and the path of the types will be in a straight line longitudinal of said 100 stripe *b*.

From the "all red" printing position last explained, the mechanism may be restored or returned successively into the neutral position indicated in Fig. 6, the "all black" 105 position (Fig. 5), or the "variegated or parti-colored" position (Fig. 4). The compressed spring 100 acts to move the switch member 78 leftward from the "all red" position until it has reached normal position (Fig. 5), 110 while the switch member 85 is positively actuated through the various return steps to the position indicated in Fig. 4 by the slide rod 89. The tapered portion 66 of the eccentric member 64 enables the latter to effect 115 an easy and certain reengagement with the strap in the link 60.

Although I have explained and illustrated the various positions of the mechanism in the order in which they successively occur, 120 it is to be understood that the devices may be operated in any order desired. For example, the handle 106 may be swung from the position indicated in Fig. 9 to that indicated in Fig. 12, thereby passing directly 125 from the "parti-colored" to the "all red" position, and vice versa; or the shift may be made from any other position to the desired position as necessity requires.

It is further to be understood that though 130

I have explained the preferable mode of using the stop device 118 in connection with the crank arm 105, yet said stop device may be manipulated in any other manner as may be desired. For example, the crank arm 105 may be turned with one hand and simultaneously the stop device may be manipulated with the other hand, or the stop device may be turned by the thumb wheel 124 thereby camming the crank arm 105 from, say, the position indicated in Fig. 9 to that in Fig. 10, or from that in Fig. 10 to that in Fig. 11. Furthermore, if desired, the handle 106 may be manipulated without employing the stop member 118 at all. The stop member 118 serves both as a stop affording a fixed abutment for the crank arm 105 and also as an indicating means, being so proportioned that when turned to the various positions hitherto described it serves to indicate what section or part of the ribbon will be utilized when the crank arm 105 is brought into contact with said stop member, hence I prefer the latter.

Various changes may be effected in the construction, combination and arrangements of parts, and some parts may be used without other parts, all without departing from the spirit and scope of my invention.

What I claim as new and desire to secure by Letters Patent, is:—

1. In a typewriting machine, the combination of printing keys, a ribbon vibrator, actuating means movable by the printing keys and normally in operative connection with said vibrator, other actuating means movable by the printing keys and normally out of operative connection with said vibrator, and switch mechanism for disconnecting the first mentioned means from the ribbon vibrator, for connecting the last mentioned means with said ribbon vibrator and for rendering both of said means inoperative on said ribbon vibrator at the same time.
2. In a typewriting machine, the combination of a ribbon vibrator, a key actuated universal bar, two independent means operative by the universal bar and between said universal bar and said ribbon vibrator, for separately operating said vibrator and both of which means are adapted to be inoperative on said ribbon vibrator at the same time, and hand operated means for controlling said independent means to render either operative or both at the same time inoperative.
3. In a typewriting machine, the combination of printing keys, a ribbon vibrator, means actuated by the printing keys for throwing said vibrator a given distance, other means actuated by the printing keys for throwing said vibrator a different distance, and hand actuated means for switching one of said means out of operative relation with said vibrator, whereby said vi-

brator is rendered inoperative, and for thereafter switching the other of said means into operative relation with said ribbon vibrator.

4. In a typewriting machine, the combination of a ribbon vibrator adapted to be moved a predetermined extent so that the types will strike along one portion of the ribbon and also adapted to be moved to another predetermined extent so that the types will strike along another portion of the ribbon, duplex means interchangeable at will for actuating said ribbon vibrator, printing keys adapted to move said duplex means and means for rendering said duplex means simultaneously inoperative.

5. In a typewriting machine, the combination of printing keys, a ribbon vibrator movable different distances from normal position, a means actuated by the printing keys for moving said vibrator one of said distances, a separate means actuated by the printing keys for moving it the other of said distances, and hand actuated means for throwing one vibrator moving means out of operative relation with the ribbon vibrator whereby said vibrator is rendered inoperative and for thereafter throwing the other vibrator moving means into operative relation with said vibrator.

6. In a typewriting machine, the combination of a ribbon vibrator, an universal bar, sets of devices actuated by the universal bar and intermediate said universal bar and said ribbon vibrator, and printing keys for operating said universal bar, one set of said intermediate sets of devices being operative to throw the ribbon vibrator a predetermined distance, and another set of said devices being operative to throw said vibrator a different distance, and said sets of intermediate devices being arranged and adapted to be connected with said vibrator at will and to be simultaneously out of connection therewith.

7. In a typewriting machine, the combination of a ribbon vibrator, an universal bar, printing key levers for operating the same, and a duplex vibrator actuating mechanism movable by the printing key levers, one part of which mechanism is out of operation when the other part is in operation and both parts of which may be out of operation at the same time.

8. In a typewriting machine, the combination of a ribbon vibrator, an universal bar, printing key levers for actuating said universal bar, and link and lever mechanism actuated by the universal bar and between said universal bar and said ribbon vibrator, one element of said link and lever mechanism being single and the other double and one member of said double element being normally inoperative and the other member normally operative, means for reversing this condition of the parts, and means for

rendering both of said members of said double element simultaneously inoperative, the construction being such that when said reversing means is actuated the link element 5 is positively attached to or detached from the lever element.

9. In a typewriting machine, the combination of a ribbon vibrator, an operating lever, means operative thereon to vibrate it 10 and normally in operative engagement therewith, means operative on said lever to vibrate it and normally out of engagement therewith, and means for disengaging the first mentioned means and thereby rendering the vibrator inoperative for the time being and for thereafter engaging the second mentioned means with said vibrator operating lever.

10. In a typewriting machine, the combination of a ribbon vibrator, a lever for operating the same, a pair of links for operating said lever alternately, a universal bar connected to said links and operable to actuate them, printing key levers adapted to 25 actuate said universal bar, and means for rendering both of said links simultaneously inoperative.

11. In a typewriting machine, the combination of printing keys, a ribbon vibrator, 30 a lever for actuating the same, a means actuated by the printing keys and operative upon said lever at a predetermined distance from its fulcrum, a second means actuated by the printing keys and operative upon 35 said lever at a different predetermined distance from its fulcrum, means for shifting said operating means alternately into and out of engagement with said lever and capable also of rendering both of said operating 40 means inoperative at the same time.

12. In a typewriting machine, the combination of a ribbon vibrator, a lever for operating the same, a key actuated universal bar, and a pair of links connected to and actuated by said universal bar, one of said 45 links being adapted to operate upon one part of said lever to throw the vibrator a predetermined distance, the other of said links being adapted to operate on another 50 part of said lever to throw the vibrator a different predetermined distance, and the construction being such that both of said links may be rendered inoperative simultaneously.

55 13. In a typewriting machine, the combination of a ribbon vibrator, a lever for operating the same, a key actuated universal bar, a pair of links connected to and actuated by said universal bar, one of said links 60 being adapted to operate upon one part of said lever to throw the vibrator a predetermined distance and the other link being adapted to operate on another part of said lever to throw said vibrator a different predetermined distance, and hand actuated 65

means for throwing one link out of engagement with said lever and thereby rendering said lever inoperative and for thereafter throwing the other link into engagement with said lever.

14. In a typewriting machine, the combination of a ribbon vibrator, a lever for actuating the same, a link adapted to operate automatically on said lever at progressively increasing and decreasing distances from the 70 fulcrum of said lever, means for moving said link to cause it to operate on said lever to vibrate the latter on its fulcrum, a second link normally disconnected from said lever but adapted to be connected therewith, and 75 means for throwing out of operative relation the means for moving said first mentioned link progressively toward and from the fulcrum of said lever, for thereafter disconnecting said first mentioned link from said 80 lever whereby said lever is rendered inoperative and for thereafter connecting said second link with said lever.

15. In a typewriting machine, the combination of a ribbon vibrator, a slotted lever 90 connected therewith, a link adapted to move back and forth in the slot of said lever and to operate on said lever, an eccentric for controlling said movements, a second link also adapted to operate on said lever, and 95 means adapted to disconnect the eccentric from its associate link and also adapted to disconnect said link from said lever, thereby rendering the latter inoperative, and further adapted to connect thereafter the second 100 mentioned link with said lever.

16. In a typewriting machine, the combination of printing keys, a ribbon vibrator, means for throwing it up and down different distances including a pair of operative 105 links actuated by the printing keys, a slide positively connected with said links and maintaining them in a fixed transverse relation to each other, said slide being adapted to cause the disengagement of one link and 110 the engagement of the other link, and means mounted exteriorly of the machine for operating said slide.

17. In a typewriting machine, the combination of a ribbon vibrator, a lever for operating it, a pair of links for operating said lever alternatively, printing keys adapted to actuate said links, a slide positively connected with said links and maintaining them 115 a fixed distance apart, and a hand device for operating said slide.

18. In a typewriting machine, the combination of a ribbon vibrator, an operating lever therefor, a pair of links adapted to engage said lever alternatively, one of said links 125 having a strap, a power shaft, an eccentric adapted to slide on said shaft, a slide adapted to move said eccentric, devices adapted to control the movements of said links transversely of said lever, said devices being sep- 130

- arate from said slide and controlled by the latter, and means for controlling said slide.
19. In a typewriting machine, the combination of printing keys, a ribbon vibrator, 5 actuating means normally in operative connection therewith and movable by the printing keys, other actuating means normally out of operative connection with said vibrator and movable by the printing keys, and 10 switch mechanism positively connected with said actuating means and adapted to disconnect the first mentioned means from the ribbon vibrator and to connect the last mentioned means with said ribbon vibrator.
- 15 20. In a typewriting machine, the combination of printing keys, a ribbon vibrator, actuating means normally in operative connection therewith, other actuating means normally out of operative connection there- 20 with, both said actuating means being movable by the printing keys, switch mechanism positively connected with said actuating means and adapted to disconnect the first mentioned means from the ribbon vibrator 25 and to connect the last mentioned means with said ribbon vibrator, and further adapted to render both of said means inoperative on said ribbon vibrator at the same time.
- 30 21. In a typewriting machine, the combination of printing keys, a ribbon vibrator movable different distances from normal position, means actuated by the printing keys for moving said vibrator one of said distances, a separate means actuated by the printing keys for moving it the other of said distances, and hand actuated means positively connected with both of said moving means and adapted to throw one of said 35 moving means out of operative relation with the ribbon vibrator and to throw the other moving means into operative relation with said vibrator.
22. In a typewriting machine, the combination of a ribbon vibrator, a lever for operating the same, a pair of links for operating said lever alternatively, a universal bar connected to and operable to move said links, printing key levers adapted to actuate said 45 universal bar, and means constantly engaged with both said links and adapted to render them simultaneously inoperative.
- 50 23. In a typewriting machine, the combination of a ribbon vibrator, a lever for operating the same, a key actuated universal bar, a pair of links connected to and movable by said universal bar, one of said links being adapted to operate on one part of said lever to throw the vibrator a predetermined distance and the other link being adapted to 55 operate on another part of said lever to throw said vibrator a different predetermined distance, and hand actuated means constantly engaged with said links and 60 maintaining them a fixed distance apart,
- 70 said means being adapted to throw one link out of engagement with said lever, thereby rendering the latter inoperative, and to thereafter throw the other link into engagement with said lever.
- 75 24. In a typewriting machine, the combination of a ribbon vibrator, an operating lever therefor, a link adapted to engage said lever, said link having a strap, an eccentric adapted to engage with said strap, a switch- 80 ing member adapted to disconnect the eccentric from the link, a second link, and a second switching member adapted to disconnect said first named link from said lever and to connect said second link with said lever.
- 85 25. In a typewriting machine, the combination of a ribbon vibrator, an operating lever therefor, a link adapted to engage said lever, said link having a strap, an eccentric adapted to engage with said strap, a switch- 90 ing member adapted to disconnect the eccentric from the link, a second link, a second switching member adapted to be actuated by the first mentioned switching member, said second switching member being further adapted to disconnect said first named link from said lever and to connect the other link with said lever.
- 95 26. In a typewriting machine, the combination of a ribbon vibrator, an operating lever therefor, a link adapted to engage said lever, said link having a strap, an eccentric adapted to engage with said strap, a switch- 100 ing member adapted to disconnect the eccentric from the link, a slide rod positively connected with said switching member, said slide rod being operable from the front of the machine, a second link, a second switching member connected with both said links and adapted to maintain them a fixed distance apart, a sleeve movable lengthwise of said slide rod, positive connections between said sleeve and said second switching member, and means for causing said sleeve to 105 move with said slide rod.
- 110 27. In a typewriting machine, the combination of a ribbon vibrator, an operating lever therefor, a link adapted to engage said lever, said link having a strap, an eccentric adapted to engage with said strap, a switch- 115 ing member adapted to disconnect the eccentric from the link, a slide rod connected at one end with said switching member, a rock shaft connected with said slide rod and having an operating handle, and a positioning member on said rock shaft.
- 120 28. In a typewriting machine, the combination of a ribbon vibrator, an operating lever therefor, a link adapted to engage said lever, said link having a strap, an eccentric adapted to engage with said strap, a switch- 125 ing member adapted to disconnect the eccentric from the link, a slide rod connected at one end with said switching member, a rock shaft connected at one end with said slide 130

rod and having an operating handle, a positioning member on said rock shaft, and one or more movable abutments serving as fixed stops for the handle of the rock shaft.

- 5 29. In a typewriting machine, the combination of a ribbon vibrator, an operating lever therefor, a link adapted to engage said lever, said link having a strap, an eccentric adapted to engage with said strap, a switching member adapted to disconnect the eccentric from the link, a second link, a second switching member controlling the position of both said links transversely of said lever and controlled in turn by said first named switching member, a slide rod connected with said first named switching member, a rock shaft adapted to actuate said slide rod, said rock shaft being provided with a handle at the front of the machine, a positioning member rigid on said rock shaft, and means for holding said positioning member in any one of a plurality of predetermined positions.

- 25 30. In a typewriting machine, the combination of a ribbon vibrator, an operating lever therefor, a link adapted to engage said lever, said link having a strap, an eccentric adapted to engage with said strap, a switching member adapted to disconnect the eccentric from the link, a second link, a second switching member controlling the position of both said links transversely of said lever and controlled in turn by said first named switching member, a slide rod connected with said first named switching member, a rock shaft adapted to actuate said slide rod, said rock shaft being provided with a handle at the front of the machine, a positioning member, and a locking spring adapted to hold said positioning member in any one of a plurality of predetermined positions.

- 35 31. In a typewriting machine, the combination of a ribbon vibrator, an operating lever therefor, a link adapted to engage said lever, said link having a strap, an eccentric adapted to engage with said strap, a switching member adapted to disconnect the eccentric from the link, a second link, a second switching member controlling the position of both said links transversely of said lever and controlled in turn by said first named switching member, a slide rod connected with said first named switching member, a rock shaft adapted to actuate said slide rod, said rock shaft being provided with a handle at the front of the machine, a positioning member for controlling the rotary position of said rock shaft, and devices for indicating the rotary position of said rock shaft.

- 40 60 32. In a typewriting machine, the combination of a ribbon vibrator, an operating lever therefor, a link adapted to engage said lever, said link having a strap, an eccentric adapted to engage with said strap, a switching member adapted to disconnect the ec-

centric from the link, a second link, a second switching member controlling the position of both said links transversely of said lever and controlled in turn by said first named switching member, a slide rod connected with 70 said first named switching member, a rock shaft adapted to actuate said slide rod, said rock shaft being provided with a handle at the front of the machine, a positioning member for determining one or more predetermined rotary positions of said rock shaft, and devices for maintaining said rock shaft in said predetermined positions.

75 33. In a typewriting machine, the combination of a ribbon vibrator, an operating lever 80 therefor, a link adapted to engage said lever, said link having a strap, an eccentric adapted to engage with said strap, a switching member adapted to disconnect the eccentric from the link, a second link, a second 85 switching member controlling the position of both said links transversely of said lever and controlled in turn by said first mentioned switching member, a slide rod connected with said first mentioned switching member, a rock shaft adapted to actuate 90 said slide rod, said rock shaft being provided with a handle at the front of the machine, a positioning member for determining one or more predetermined rotary positions 95 of said rock shaft, devices for maintaining said rock shaft in said predetermined positions, and one or more abutments adapted to contact with the handle portion of said rock shaft and to serve as positive stops for 100 said shaft.

34. In a typewriting machine, the combination of a ribbon vibrator, means for automatically giving a variable progressive throw to said vibrator, means for throwing 105 said vibrator to one or more predetermined positions, and a rotary stop member having a plurality of stops which serve as fixed abutments for controlling the adjustment of both the above named means.

110 35. In a typewriting machine, the combination of printing keys, a ribbon vibrator, actuating means movable by the printing keys and normally in operative connection with said vibrator, other actuating means 115 movable by the printing keys and normally out of operative connection with said vibrator, switching devices for shifting said actuating means, mechanism for controlling said devices, and a rotary indicating device 120 co-operating with said mechanism.

36. In a typewriting machine, the combination of printing keys, a ribbon vibrator, actuating means movable by the printing keys and normally in operative connection 125 with said vibrator, other actuating means movable by the printing keys and normally out of operative connection with said vibrator, switching devices for shifting said actuating means, mechanism for controlling 130

said devices, and a frictional, hand actuated, rotary stop for positioning said devices.

37. In a typewriting machine, the combination of printing keys, a ribbon vibrator, 5 an operating member for said ribbon vibrator, a plurality of reciprocatory links for operating said operating member, said links being movable by the printing keys, a shiftable guide member for said links, and means 10 for shifting said guide member to connect one or another of said links to said operating member, or to render said member entirely free from said links.

38. In a typewriting machine, the combination of a ribbon vibrator, a universal bar, 15 printing key levers for operating the same, and a duplex vibrator actuating mechanism movable by the printing key levers, one part of which mechanism is out of operation when 20 the other part is in operation and both parts

of which may be out of operation at the same time, both parts of said duplex vibrator actuating mechanism being operable by all the printing key levers.

39. The combination of a ribbon vibrator, 25 two separate means whereby the vibrator may be thrown different distances, printing keys adapted to actuate each of said separate means, and means for rendering the vibrator inoperative by freeing the same from both 30 said separate means, whereby the types may be operated without striking the ribbon.

Signed at Syracuse, in the county of Onondaga, and State of New York, this 6th day of February A. D. 1905.

HENRY W. MERRITT.
